RATION OF PENNSYLVANIA.

ELECTRIC SWITCH.

1,130,204.

Specification of Letters Patent. Patented Mar. 2, 1915.

Application filed October 31, 1910. Serial No. 590,097.

To all whom it may concern:

Be it known that we, HJALMAR RUDMAN SCHULTZ and FREDERICK BRERETON HOLT, subjects, respectively, of the King of Sweden and the King of England, and residents of Manchester, in the county of Lancaster, England, have invented a new and useful Improvement in Electric Switches, of which the following is a specification.

10 Our invention relates to electric switches and particularly to switches which are employed in connection with high-tension circuits and have all live parts completely enclosed. In these switches, it is usual to provide a coil or coils in the high-tension circuit having an armature or plunger which is adapted to act upon a trip mechanism and open the switch when the current in the circuit exceeds a predetermined limit, and to 15 also provide a coil which is included in the secondary circuit of a shunt transformer, mounted in the switch case, and serves to hold the trip mechanism of the switch normally in locking position but releases it 20 when the voltage of the circuit falls below a certain limit. The above mentioned coils will be hereinafter referred to as an overload coil and a no-voltage coil, respectively. The switch is also usually provided with an 25 ammeter which indicates the current passing in the high-tension circuit.

According to the present invention, the construction of the switch is simplified and the manufacture facilitated and cheapened 30 by mechanically supporting the overload coil and the ammeter directly upon the high-tension conductor to which they are electrically connected.

40 A further feature of the invention consists in locating the trip mechanism in a separate casing which is readily accessible for inspection and adjustment, the actuating members for the said mechanism being entirely insulated from those portions of the switch which are subjected to a high potential.

The invention is illustrated in the accompanying drawing, in which—

Figure 1 is a view in side elevation, partly 45 sectional, of a switch constructed in accordance with the invention, and Fig. 2 is a detail view, in end elevation, of a portion of the mechanism shown in Fig. 1.

Referring now to the drawing, the switch 50 mechanism is inclosed in a casing compris-

ing a body portion 1, an oil tank 2, within which the switch contact terminals are located, and a hood or cap 3. The high-tension terminals 4 and 5 of the switch enter the body portion 1 through insulating bushings 6 and terminate, within the said body portion, in rods 7 and 8, respectively.

The stationary contact terminals of the switch are indicated at 9 and 10 and are mounted upon insulated supports 11, within the oil tank 2, the movable member of the switch comprising an insulated bridge piece 12, carrying contact terminals 13 and 14 which are adapted to engage the respective stationary contact terminals 9 and 10 when the switch is closed. The bridge piece 12 is arranged to be raised and lowered, to close and open the switch, by means of rods 15 which are operated by levers 16, one end of each of which is attached to a shaft 17 that is actuated by means of an external handle (not shown).

The lever 16 is shown in the drawing as being in a position corresponding to the closed position of the switch and is normally retained in this position by means of suitable mechanism 18^a which is located in an auxiliary casing 18. The free end of lever 16 is embraced by the prongs of a bifurcated latch 38 that is pivotally mounted in the casing 18. The upper edge of the non-bifurcated end of the latch 38 is normally engaged by a roller 39 with which a pivotally mounted locking lever 40 is provided, the locking engagement being insured by a weight 41 at one end of the lever. The roller 39 of the locking lever 40 is moved out of engagement with the latch 38 by reason of the engagement of the core 42 of a solenoid 43 with the free end of an arm 44 of the lever, such engagement being effected by gravity when the voltage of the circuit to which the solenoid is connected fails or becomes reduced to a predetermined minimum value.

The locking lever may also be actuated either manually or electromagnetically, to release the latch 38 by rocking a bell crank lever 45 on its pivot to cause the end of one of its arms 46 to effect operative engagement with a pin 47 on the locking lever 40. The lever 45 is rocked to release the latch from the locking lever by a lever 35 by a means and in a manner to be hereinafter set forth.

The rod 7 forming a continuation of the high-tension terminal 4 is considerably longer than the rod 8 and serves to support the overload coil 19 and the ammeter 20 of the switch in the following manner: The overload coil 19 comprises a helix of heavy copper conductor, one end 21 of which is bent downward and riveted to a connector 22 that surrounds the rod 7 and is secured thereto by lock nuts 23. The other end 24 of the overload coil 19 is attached, by means of bolts 25, to a conductor 26 that constitutes one of the terminals of the ammeter 20. The latter is mainly supported by means of a bar 27 which also connects the other terminal of the ammeter to one of the stationary contact terminals 10 of the switch, the other contact terminal 9 being connected to the rod 8 by a bar 28. The ammeter 20 may also have a steadyng or bracing connection to a bracket 49, as shown in the drawing. The bar 27 is supported on an extension 29 of the rod 7, an insulating sleeve 30 being interposed between the extension 29 and the bar 27. The bar 27 also serves to support the magnetizable frame 31 of the overload coil 19, the said frame being attached to the bar 27 by means of rivets, as shown in the drawing.

The complete circuit through the apparatus, when the switch is closed, may be traced as follows: from the high-tension terminal 4, through the rod 7, connector 22, terminal 21, overload coil 19, terminal 24, conductor 26, ammeter 20, bar 27, stationary contact terminal 10, movable contact terminal 14, bridge piece 12, movable contact terminal 13, stationary contact terminal 9 and bar 28, to the other high-tension terminal 5. The insulating sleeve 30 which is interposed between the extension 29 and the bar 27, is provided for the purpose of withstanding the small drop in voltage through the overload coil 19 and the ammeter 20. The overload tripping device comprises, in addition to the coil 19 and its frame 31, a movable core 32 which, when an overload occurs, actuates an arm 33 that is mounted on a shaft 34 and is well insulated therefrom. The shaft 34 is connected to a lever 35 the free end of which projects within the casing 18 and serves to actuate the opening mechanism of the switch, upon the occurrence of an overload. The no-voltage coil 36 of the switch, previously referred to, is also located within the casing 18 and is supplied with current from the high-tension circuit, through a shunt transformer 36 and high-tension fuses 37.

As will be seen from the drawings, all the parts of the apparatus which are subject to a high potential are located within the main switch casing 1, 2, 3, the casing 18 which contains the operating mechanism being entirely isolated from all these parts. The

casing 18, which contains the locking and releasing mechanism of the switch, is arranged to be readily removable and, as it is in connection with this part of the apparatus that difficulties arise, the possibility of inspecting and adjusting the mechanism, which is afforded by this construction, is of great advantage, since it may be performed while the switch is connected to the high-tension circuit, owing to the fact that the mechanism contained within the casing 18 is entirely isolated from those parts of the switch which are subject to a high potential. The switch may be, and preferably is, provided with arrangements for preventing the removal of the oil tank 2 and the hood 3, so long as the switch is in its closed position and is connected to the high tension circuit, arrangements of this kind being well known in the art.

The structural details for carrying the invention into practice may evidently be considerably varied from those above described without exceeding the scope of the invention.

We claim as our invention:

1. Electric switching apparatus for high-tension circuits comprising an overload tripping coil having an electrical connection to one of the high-tension circuit leads and supported thereby, an ammeter mainly supported by said high tension lead by one of its conducting leads from which it is insulated, and a casing for said apparatus.

2. In a switch for high-potential circuits, a main casing having terminal rods mounted in one of its walls, an overload magnet supported upon one of said rods and electrically connected thereto by a single means, a measuring instrument mainly supported upon one of said terminal rods and electrically connected to the other rod by the supporting connection and the separable switch members.

3. In a switch for high-potential circuits, a main casing having terminal rods at one side and an auxiliary casing at the opposite side, stationary and movable contact terminals, an overload magnet supported by one of said terminal rods, locking and releasing mechanism for said movable contact terminals located in said auxiliary casing, and an operating lever for said releasing mechanism that projects into said auxiliary casing and is actuated by said overload magnet.

4. In a switch for high-potential circuits, a main casing, an auxiliary casing, contact terminals and an overload magnet in said main casing, and a no-voltage magnet and locking and releasing mechanism in said auxiliary casing.

5. In a switch for electrical circuits, the combination with a main casing having terminal rods mounted in one of its walls, of

an overload magnet supported by one of said rods, a supplemental casing, a no-voltage magnet and locking and releasing devices in said supplemental casing, and a tripping lever interposed between said releasing devices and said overload magnet.

5 6. In a switch for electrical circuits, the combination with a main casing and a supplemental casing, of an overload magnet located in said main casing, a no-voltage coil and locking and releasing devices located in said supplemental casing, and a tripping lever interposed between said overload magnet and said releasing devices.

10 7. In a switch for high-potential circuits, a main casing having terminals inserted therein, an auxiliary casing, coöperating contact members and an overload magnet in said main casing, means for supporting said overload magnet upon said terminals inserted in said casing, and a no-voltage mag-

net and locking and releasing mechanism in said auxiliary casing.

8. In a switch for high-potential circuits, a main casing having terminals inserted 25 therein, an auxiliary casing, coöperating contact members and an overload magnet in said main casing, means for supporting said overload magnet upon said terminals inserted in said casing, a no-voltage magnet 30 located in said auxiliary casing, and means within said auxiliary casing for releasing said contact member in response to the operation of both magnets.

In testimony whereof, we have hereunto 35 subscribed our names this 14th day of October 1910.
